UNITED STATES PATENT OFFICE.

EMIL KAUFMANN, OF NEW YORK, N. Y.

SPRING-PUTTEE.

1,276,662.

Specification of Letters Patent. Patented Aug. 20, 1918.

Application filed April 10, 1918. Serial No. 227,664.

To all whom it may concern:

Be it known that I, EMIL KAUFMANN, a subject of the Emperor of Germany, but having declared my intention to become a 5 citizen of the United States, and a resident of the city of New York, borough of Manhattan, in the county and State of New York, have invented a new and Improved Spring-Puttee, of which the following is a 10 full, clear, and exact description.

This invention relates to leggings or puttees such as are commonly worn by soldiers or officers of the army or by sportsmen, and has particular reference to that type or de- 15 sign of puttee in which the main portion or body of the device is of a one piece or relatively rigid material as distinguished from a legging which consists of a spiral wrapping.

20 More specifically the improvement relates to puttees in which there is provided a spring member arranged substantially parallel to the free edge of the outer flap portion which serves as a locking member in connection 25 with the other flap and also as a stay or stiffener for the front part of the structure.

Among the objects of this present invention, therefore, is to provide improved means to prevent the point or prong of the 30 spring from abrading, scratching or tearing the facing material of that portion of the body of the puttee adjacent to the keeper or socket into which the point of the spring is inserted.

35 With the foregoing and other objects in view the invention consists in the arrangement and combination of parts hereinafter described and claimed, and while the invention is not restricted to the exact details of 40 construction disclosed or suggested herein, still for the purpose of illustrating a practical embodiment thereof reference is had to the accompanying drawings, in which like reference characters designate the same parts in the several views, and in which— 45

Figure 1 is a perspective view showing a puttee having my improvement embodied therein.

50 Fig. 2 is an enlarged front elevation of the keeper portion of the puttee.

Fig. 3 is a vertical section of the same on the line 3—3; and

Fig. 4 is a horizontal section on the line 4—4 of Fig. 3.

55 In carrying out this improvement in a practical embodiment it is to be understood

that the puttee 10 in its general aspects may be of any suitable or well known design or construction such as sole leather, leather faced with khaki, or any other suitable structural composition. In a puttee of this design it is common to employ a steel rib or spring 11 which is carried within the outer flap 12 and substantially coextensive vertically therewith, while the point 13 of the 60 spring projects within the inner face of this portion of the device so as to be projected downward into a loop or keeper 14 fixed on the outside of the inner flap 15 near the ankle end thereof. Thus the spring 70 and keeper constitute a quick and effective means for locking the lower portion of the puttee in closed ankle fitting position. A strap 16 carried by the top portion serves 75 then to complete the locking means and prevents the accidental separation of the point of the spring from the keeper.

As ordinarily constructed the extreme point of the spring during the action of inserting it into the keeper is almost sure to 80 abrade or even gouge a ragged hole through the face of the body of the puttee just above the keeper and thereby the device is rendered more or less unsightly and the efficiency consequently of the puttee is likewise affected. 85 My improvement, therefore, consists in so constructing the keeper as to prevent all such damaging results due to the point of the spring.

17 indicates a plate preferably of metal 90 and having a flattened or beveled upper end 18. This plate may be secured to the outer face of the puttee in any suitable manner, but I have found by providing a pair of slots 19 in the side portions of the plate the side 95 portions 14' of the keeper will be passed inward therethrough prior to clenching over on the inside of the construction, thereby the tongues 20 of the keeper which are of less vertical length than the keeper as a 100 whole serve a dual purpose of locking the plate snugly against the face of the puttee as well as the locking of the keeper itself. The plate may extend to any desired point or distance above the top of the keeper and 105 with the end thereof beveled as indicated I secure two immediate results or advantages. Primarily the point 13 of the spring in the act of locking the puttee will strike against the beveled face of the plate instead of the 110 leather or fabric and thence it will be guided along the plate directly into the

keeper. The beveling of the upper end of the plate offsets any liability of the plate constituting an obstruction to the passage of the point along the plate or into the keeper in case the wearer awkwardly or carelessly causes such point to strike against the face of the puttee prior to its passage into the keeper or along the plate. It will be appreciated, however, that the plate constitutes an effective guard serving to prevent the spring point from gouging a hole into the face of the leather or fabric.

Furthermore the plate in its coaction or coöperation with the keeper serves as a reinforcement and hence a means to steady or stiffen the effect of the keeper with respect to the body of the puttee.

I claim:

1. The combination with the body of the puttee having a metal keeper fixed thereto along one flap and a pointed spring fixed to the opposite flap for coöperation with the keeper, of a metal plate fixed to the

first mentioned flap by means of said keeper and having its upper end beveled and extending above the keeper constituting a guard for the puttee body and a guide for the point of the spring in its movement into locking position in the keeper.

2. The combination with the body of a puttee having a metal keeper fixed thereto along one flap and a pointed spring fixed to the opposite flap for coöperation with the keeper, said keeper including side portions terminating in tongues passing inward through the body of the puttee and clutching upon the inside thereof, of a metal plate on the outside of the first-mentioned flap and having a pair of slots through which said tongues of the keeper pass and whereby the plate is secured against the body of the puttee, the upper end of the plate extending above the keeper and constituting a guard to protect the body of the puttee from damage from the point of the spring.

EMIL KAUFMANN.
